[57] CLAIM

The ornamental design for a modularized visual training aid for classroom instruction, as shown and described.

DESCRIPTION

FIG. 1 is a rear perspective view of a modularized visual training aid for classroom instruction in an elevated position;

FIG. 2 is a bottom plan view thereof;

FIG. 3 is a right side elevational view thereof;

FIG. 4 is a front elevational view thereof;

FIG. 5 is a left side elevational view thereof;

FIG. 6 is a rear elevational view thereof;

FIG. 7 is a top plan view thereof;

FIG. 8 is a front perspective view thereof, in an alternate, lowered position;

FIG. 9 is a bottom plan view thereof;

FIG. 10 is a left side elevational view thereof;

FIG. 11 is a rear elevational view thereof;

FIG. 12 is a right side elevational view thereof;

FIG. 13 is a front elevational view thereof; and,

FIG. 14 is a top plan view thereof.
